(57) **CLAIM**

The ornamental design for a solar and thermal mirror-cell panel, as shown and described.

DESCRIPTION

FIG. 1 is a top front perspective view of a solar and thermal mirror-cell panel showing my new design;

FIG. 2 is a bottom rear perspective view thereof;

FIG. 3 is a right elevational view thereof; the left side elevational view thereof being a mirror image of the right side shown;

FIG. 4 is a front elevational view thereof; the back side elevational view thereof being a mirror image of the right side shown;

FIG. 5 is a bottom plan view thereof; and,

FIG. 6 is a top plan view thereof.

The broken lines depicting the hole in FIGS. 1-2 and FIGS. 5-6 form no part of the claimed design.
